UNITED STATES PATENT OFFICE.

ALFRED MICHAEL, OF NEW YORK, N. Y., ASSIGNOR TO EAGLE PENCIL COMPANY, OF NEW YORK, N. Y.

PENCIL.

1,406,056.

Specification of Letters Patent. Patented Feb. 7, 1922.

Application filed March 26, 1921. Serial No. 455,735.

To all whom it may concern:

Be it known that I, ALFRED MICHAEL, a citizen of the United States, residing at New York, in the county and State of New York, 5 have invented certain new and useful Improvements in Pencils, of which the following is a full, clear, and exact description.

The invention which forms the subject of this application for Letters Patent is an 10 improvement in pencils of the mechanical type in the making of which the object has been primarily to reduce the weight of the pencil as a whole, to simplify the construction of its constituent parts and to produce 15 a mechanical combination which is more certain in its operation and more durable than similar devices which have heretofore been in use. In general, the construction and its mode of operation follow known lines, but 20 its distinctly novel features are in the design of its elements or working parts, and these may be most readily understood from the detailed description in connection with the drawing which follows—

25 In the annexed drawing,

Fig. 1 is a view in elevation of the complete pencil.

Fig. 2 is a sectional view of the case exhibiting the interior parts or mechanism in 30 elevation.

Fig. 3 is a central vertical section of the entire device.

Fig. 4 is a sectional view on the line 4—4 of Fig. 3.

35 Fig. 5 is a sectional view on the line 5—5 of Fig. 3, and

Fig. 6 is an enlarged detail view in section of portions of the interior mechanism.

The main case of the pencil is in the form 40 of a plain metal cylinder 1. Into this cylinder is forced a sleeve 2 preferably of wood which is incapable of turning in the case, although so far as the improvement in its broader aspects is concerned this sleeve may 45 be of other material such as metal and secured against rotation in other ways.

Assuming the material to be of wood, it has a recess at its upper or rear end into 50 which the straight shank of a clip 3 is forced through a small transverse slot 4 in the case and by this means the clip is held firmly in position and a most economical and satisfactory means secured for fastening the clip in permanent operative relation in the case.

55 The sleeve 2 contains a slot 5 of proper

length to meet the conditions of use, and a short metal cylinder or sleeve 6 to which is attached the end of a spiral wire 7 is passed into the upper end of the case, the spiral wire extending down through the bore of the 60 sleeve. Within the spiral wire is a follower wire 8 having a projection or bent portion 9 that is engaged by the convolutions of the wire and which enters the slot 5. The sleeve 2 carries at its forward or lower end a bushing 13, which is threaded at its free end 13'. The sleeve 2, the bushing 13, the carrier 6, the spiral wire 7, and the follower wire 8, are assembled first and then forced into the case, the sleeve being held in place by the 65 bushing, after which the end edge of the case is turned down into a circular groove 10 in the carrier 6 by which means the said carrier and its attached parts are permanently secured to the case but are capable of 70 being readily rotated therein.

A piece of india rubber 11 is forced into the open end of the sleeve or carrier 6 and a cap 12 is forced down over the same and the carrier until its beaded edge fits down 80 over the end edge of the case 1, as shown. The frictional engagement between the cap 12 and the sleeve 6 permits the latter to be rotated by the rotary movement of the cap with the result that by turning the cap the 85 follower wire 8 may be advanced or retracted by the engagement of the projection 9 with the spiral wire.

With the bushing 13 internally threaded at its forward or free end, it engages an 90 annular externally threaded cylindrical lead reservoir or magazine 14, the forward end of which is shouldered or stepped as shown at 14' in Fig. 2. Passing entirely through this magazine 14 is a tube 15 which fits 95 snugly the forward contracted end of the same and is itself then tapered and extends down through the tapered end of an extension 16 of the case 1, its end edges being flush with those of said extension.

100 This extension is fitted tightly over the magazine 14 and is practically inseparable therefrom. As is usual in pencils of this character the leads pass through the guide formed at the pencil tip, which as shown at 105 17 is slotted for a small fraction of an inch from the tip and then compressed to form a slightly yielding frictional guide. The tube 15 for this purpose should also have short slots as shown at 22 in Fig. 6.

The upper or rear end of the magazine 14 is internally threaded to receive a cap 18 having a central perforation through its top with downwardly extending and inwardly inclined edges forming a conical guide 19. The upper or rear end of the tube 15 is flared as shown at 20, in Fig. 6, and when the cap 18 is screwed in place this flaring end engages the conical guide 19 and the tube is aligned exactly in the center of the case. The concave upper surface of the cap also permits the follower wire 8 to enter the tube 15 even though the wire and tube are not primarily in alignment.

15 The parts thus constructed and assembled form an annular magazine in which extra leads 21 may be kept. To place a lead in the pencil the pointed extension is turned to unscrew the lead magazine. The cap 18 is removed to gain access to the magazine and being replaced a lead is simply dropped through the central perforation down through the tube 15. The follower 8 is retracted and the magazine screwed home. By then turning the cap 12 the lead is forced straight through the contracted portion of tube 15 and the open pencil tip of the pointed extension 16.

20 In this device all parts are readily and cheaply made. No unusual means are required for the permanent assembly of the parts. The latter are held in their correct positions of alignment and the pencil, as a whole, is capable of indefinite use, without 25 clogging of the tip or any derangement of the parts.

What I claim as my invention is—

1. In a mechanical pencil the combination with a case and means carried thereby for advancing or retracting a follower wire for the leads of a detachable pointed extension for the case, an annular lead magazine secured to said extension and adapted to engage with the case, a tube extending through the magazine and the extension to its open point, a perforated screw cap for the magazine having a conical guide thereon with which the end of the tube engages and by which it is centrally aligned.

2. In a mechanical pencil the combination with a case and means carried thereby for advancing or retracting a follower wire for the leads of a detachable pointed extension for the case, an annular lead magazine secured to said extension and provided with internal and external threads at its end, the external threads adapted to engage with the case, a perforated cap adapted to engage with the internal threads of the magazine, said cap having downwardly extending and inwardly inclined edges to the perforation forming a conical guide, a tube extending through the magazine and to the pointed end of the extension and having a flaring upper end adapted to engage with the conical guide on the cap and to be centrally aligned thereby when the parts are assembled.

In testimony whereof I hereto affix my signature.

ALFRED MICHAEL.
